(57) **CLAIM**

The ornamental design for a golf ball retrieval device, as shown and described.

DESCRIPTION

FIG. 1 is a side elevated view of the golf ball retrieval device in accordance with the present invention showing its use relative to a golf ball;

FIG. 2 shows a top plan view of the golf ball retrieval device;

FIG. 3 shows a bottom plan view of the golf ball retrieval device;

FIG. 4 shows a side view of the golf ball retrieval device;
FIG. 5 shows a front view of the golf ball retrieval device;
and,

FIG. 6 shows a rear view of the golf ball retrieval device.
The broken line showing of is for illustrative purposes only
and forms no part of the claimed design.
